(57) **CLAIM**

The ornamental design for a painting pad, as shown and described.

DESCRIPTION

FIG. 1 is a front, right perspective view of a painting pad in the first state, showing my new design;

FIG. 2 is a front, left perspective view thereof;

FIG. 3 is a front elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of FIG. 1;

FIG. 9 is another partial enlarged view of FIG. 1;

FIG. 10 is another partial enlarged view of FIG. 1;

FIG. 11 is another partial enlarged view of FIG. 1;

FIG. 12 is another partial enlarged view of FIG. 1;

FIG. 13 is another partial enlarged view of FIG. 1;

FIG. 14 is another partial enlarged view of FIG. 1;

FIG. 15 is another partial enlarged view of FIG. 1;

FIG. 16 is a partial enlarged view of FIG. 2;

FIG. 17 is another partial enlarged view of FIG. 2;

FIG. 18 is a partial enlarged view of FIG. 3;

FIG. 19 is a front, right perspective view of the painting pad in the second state;

FIG. 20 is a front, left perspective view thereof;

FIG. 21 is a partial enlarged view of FIG. 19; and,

FIG. 22 is a partial enlarged view of FIG. 20.

The broken lines represent the bounds of the partial enlarged views and form no part of the claimed design.

1 Claim, 15 Drawing Sheets
